RIBBON FEEDING AND REVERSING MECH-
ANISM FOR TYPEWRITING MACHINESChester W. Crumrine, Rochester, N. Y., assignor
to International Business Machines Corpora-
tion, New York, N. Y., a corporation of New
York

Application December 18, 1947, Serial No. 792,403

10 Claims. (Cl. 197—162)

1

This invention relates to typewriting machines and more particularly to ribbon feeding and reversing mechanism.

An object is to provide a ribbon feeding and reversing mechanism in which the ribbon spools may be inserted and removed more readily than the ones in ribbon mechanisms hitherto used in the art.

An object is to provide a ribbon feeding mechanism in which the ribbon spool is frictionally driven at the rim.

An object is to provide an improved reversing mechanism.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the ribbon mechanism.

Fig. 2 is a vertical section on the line 2—2 in Fig. 1 and shows the left-hand ribbon feeding unit in side elevation.

Fig. 3 is a vertical section on the line 3—3 in Fig. 1.

Fig. 4 is a front elevation of the left-hand ribbon feeding unit and shows the reversing mech-
anism in disengaged position.

Fig. 5 is a view similar to Fig. 4, but showing the reversing mechanism in engaged position.

Fig. 6 is a side elevation of a portion of the reversing mechanism associated with the right-hand and left-hand ribbon feeding units.

In Fig. 1 there is shown a pair of ribbon feed-
ing units which are mirror images of each other in respect to placement of parts and the right-
hand unit is designated RH and the left-hand unit LH. Each unit comprises a pair of side frame members such as plates 11, 12 which are connected together by riveted shouldered studs 13 at the top and by a connecting web 14 at the bottom. Conveniently the frame plates 11 and 12 may be formed from one piece of metal of which the web 14 forms the connecting part. The frame comprising the plates 11 and 12 is mounted in any suitable manner on a frame mem-
ber 15 by means of which the ribbon mechanism may be mounted as a unit removable from the machine, this frame being provided with suitable lugs 15a for the purpose of securing the frame 15 to the main frame work of the machine, not shown.

Journalized in the frame plates 11 and 12 of both units is a drive shaft 16 which, at its right-hand

2

end (Fig. 1), is provided with a bevel gear 18a meshing with a bevel gear 18 on the shaft 19 suitably journaled in a lug 11a formed in the plate 11 for the right-hand unit RH. The shaft 19 may be driven in any suitable way known in the art as, for example, by gearing to the spring drum which powers the carriage of the typewriting machine so that the shaft 19 always rotates counter-clockwise (Fig. 1) when the carriage moves in a letter spacing direction. Between the frame plates 11 and 12 of both units the shaft 16 is provided with friction drive rollers 17 which, by coopera-
tion with the edges of the ribbon spools, effect a counterclockwise movement of the spools.

The spaces between the plates 11 and 12 form pockets for the reception of the right-hand ribbon spool 20R and the left-hand ribbon spool 20L and, for the purpose of supporting the ribbon spools in the pocket and also rotatably mounting them in coaction with rollers 17, there is provided a loose roller 21 for each unit which is rotatably mounted on a stud 22 riveted to the plates 11 and 12 in each case. The rollers 21 are spaced from the driving rollers 17 a distance slightly less than the diameter of the ribbon spools 20R and 20L.

Journalized on the plate 12 at 12a (Figs. 2 and 3) is a lever 23, one arm of which is provided with a stud 23a carrying the roller 24 and the longer arm of which is similarly provided with another stud 23b and roller 25. When the ribbon spool is inserted in the pocket between the plates 11 and 12 as in Figs. 2 and 3, the rims thereof co-
operate with the rollers 17, 21, and 24 whereby rotation of the roller 17 will drive the ribbon spool 20L in a clockwise direction.

For the purpose of holding the rims of the ribbon spool 20L in engagement with the roller 17, there is provided a spring 26 (Fig. 2) which is anchored to the lever 23 and to a pin carried by the plate 12. The effect of the spring 26 is to cause roller 24 to wedge the spool 20L downwardly between the rollers 17 and 21, the roller 25 only lightly engaging the rims of the ribbon spools, if at all. The primary purpose of the roller 25 is to push the spool upwardly when it is desired to remove it or stop feeding by that spool and for this purpose a separate mechanism now to be described is provided. Both ribbon feeding units are provided with arms 23, rollers 24, 25, and springs 26.

The lever 23 for the left-hand unit is connected by a link 27 to a finger lever 28 and the lever 23 for the right-hand unit is connected by a link 27a to one arm of a bell crank 28a (Fig. 6), both

levers 28 and 28a being secured to the cross shaft 29 journaled in the plates 12. The lever 28 projects through a suitable slot in the frame 25 (Fig. 1) and a slot in the outer casing of the machine and may be grasped by the operator and lifted. When this is done, the link 27 is pushed upwardly (Figs. 2 and 6) and rocks the left-hand lever 23 clockwise (Fig. 2) whereby the roller 25 pushes up the left-hand ribbon spool 20L to stop feeding this spool or to facilitate its removal for the purpose of inserting a new ribbon. At the same time, link 27a is pulled downwardly allowing the spring 26 for the right-hand spool to rock the associated lever 26 clockwise with reference to Fig. 2 and engage the right-hand spool 20R with the right-hand roller 17.

Normally only one of the rollers 17 engages a ribbon spool and they are automatically selectively engaged with the ribbon spools, on one side or the other of the machine, to feed one or the other of the ribbon spools. The levers 28, 28a control the reversing of the ribbon by lifting one or the other of the ribbon spools 20L, 20R far enough to disengage the roller 17 from the spool which is to be idle and pushing down the other spool into engagement with the other roller. Lever 28 provides a means of reversing the ribbon manually when necessary.

Figs. 2, 3, and 6 show the condition of the parts when the left-hand spool is feeding with the left-hand lever 23 rocked counterclockwise as far as it will go whereby the roller 24 wedges the ribbon spool 20L between the left-hand rollers 17 and 21. The lever 28a which is associated with the right-hand unit RH (Fig. 1), under these conditions, forms a straightened toggle with link 27a whereby, when the arm 28 is raised, the lever 23 associated with the left-hand spool is rocked clockwise (Figs. 2 and 3) to disengage the spool 20L from its driving roller 17, and the arm 28a, by pulling down the link 27a for the right-hand unit RH, rocks the lever 23 therefor in a counterclockwise direction, considered with reference to Fig. 2, to wedge the right-hand spool 20R between the right-hand rollers 17 and 21.

The levers 28, 28a and shaft 29 are automatically shifted to effect reversal in the feeding of the ribbon by means of two links 30, 30a, the link 30 being associated with the lever 28 and the link 30a associated with the lever 28a and respectively loosely pivoted thereto so as to permit lateral movement of the links on the levers. The link 30 associated with the left-hand spool 20L is curved around the shaft 16 and at its upper end has a reduced portion loosely received in a hole or eye formed in one arm of a bell crank 31 pivoted at 12d on a lug 12c formed in the plate 12 of the left-hand spool 20L. The other arm of the bell crank 31 projects into the plane of a control lever 32 pivoted at 12e on the plate 12. The lever 32 is formed with the usual off-set lug 32a having a suitable slot through which passes the ribbon as it unwinds from the left-hand spool 20L. The control lever 32 is urged in a counterclockwise direction by a spring 33 anchored to the same pin as the spring 26. The bell crank 31 is urged in a clockwise direction by a spring 31a which maintains contact between lever 32 and lever 31, but spring 33 is stronger than spring 31. Link 30 is provided with a roller 30b which is out of the plane of, but below, the level of the teeth of a star wheel 34 secured to the shaft 16.

The right-hand unit 20R is provided with

similar parts, but in the case of the right-hand unit, the roller 30b is above the shaft 16 and in horizontal alignment with the teeth of the right-hand star wheel 34.

Bearing in mind that the shaft 16 is given an increment of rotation to feed the ribbon with each operation of the typewriting machine, it is apparent that if the right-hand spool is almost exhausted, the tension built up in the ribbon 10R ultimately will cause the control lever 32 for the right-hand spool to rock clockwise with reference to Fig. 2 and allow the bell crank 31 for the right-hand spool (Fig. 1) to rock counterclockwise under the influence of its spring, thereby placing the roller 30b for the right-hand link 30a in the path of the teeth in the right-hand star wheel 34. As a consequence of further rotation of the shaft 16, the roller 30b for the right-hand link 30a in Fig. 1 will be cammed 15 upwardly by star wheel 34, drawing up the link 38a and rocking the shaft 29 clockwise from the position of Fig. 2. This will result in pushing up the link 27 in Figs. 2 and 6 for the left-hand spool and disengaging this spool from the associated driving roller 17, thereby stopping the feeding of the ribbon. Due to the drawing upwardly of the link 38a for the right-hand unit RH, the lever 23 therefor, will be rocked counterclockwise and wedge the right-hand spool 25 between its driving roller 17 and the right-hand roller 21, thereby starting the winding of the ribbon on the right-hand spool.

These conditions will be reversed when ultimately the left-hand spool becomes empty, allowing its bell crank 31 to rock clockwise and pushing roller 30b associated therewith into the path of the teeth in the left-hand wheel 34. This will cause the link 30 in Fig. 2 to be pushed downwardly and the link 27a for the right-hand unit will be pushed upwardly, thereby stopping the feeding of the ribbon on the right-hand spool.

If the operator, in installing a new ribbon wishes to reverse the feed to insure that the ribbon immediately will start to feed in the proper direction, the lever 28 may be pushed up or down as the case may be, to manually condition the ribbon feeding mechanism for feeding in the proper direction.

50. The main advantage of the ribbon mechanism is the ease of removal of the ribbon. It is merely necessary to push the levers 32 toward the rear of the mechanism or clockwise in Fig. 2 and lift the spools out of their pockets.

55. While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A ribbon feeding mechanism comprising a pair of ribbon spools, a drive shaft having a friction drive roller for each of said spools, means associated with each spool for engaging such spool with the associated drive roller, means interconnecting said engaging means and movable between two alternate positions in one of which positions one spool is engaged with and the other disengaged from the corresponding driving roller

and in the other of which positions these conditions are reversed, means to detect exhaustion of the ribbon, and means controlled by the detection means for shifting the interconnecting means to cause the exhausted spool to be driven by its roller and the other spool to be disconnected from its roller.

2. In a ribbon mechanism, a pair of ribbon spools, a frame work including a pair of pockets, one for each spool, each pocket having a fixed guide roller and a driving roller for rotatably supporting the spool, control means including a pair of elements, one for each spool for lifting the spools out of engagement with their driving rollers to allow the spools to unwind, said means being settable in alternate positions in each of which a different one of said spools feeds while the other unwinds, means to detect exhaustion of said spools, and means rendered operative by the detection means when any spool becomes exhausted, to actuate the control means to lift the full spool from its driving roller and engage the exhausted spool with its driving roller.

3. A ribbon feeding mechanism for office machines comprising a pair of ribbon spools; a pair of detecting devices, one for each spool, for detecting exhaustion of the associated spool; a pair of friction driving rollers, each associated with one of said spools; means to drive said rollers; a pair of coupling devices, one for each spool for engaging said ribbon spools with said rollers, said coupling devices being intercoupled so that when either coupling device is effective the other is ineffective; and a pair of shift devices, one for each spool and connected to the coupling device for such spool, each shift device being rendered effective by the detecting device of the associated spool, when the latter becomes exhausted, to actuate the associated coupling device to operative position.

4. A ribbon feeding mechanism for office machines comprising a pair of ribbon spools; a pair of detecting devices, one for each spool, for detecting exhaustion of the associated spool; a pair of friction driving rollers, each associated with one of said spools; means to drive said rollers; a pair of coupling devices, one associated with each spool, for engaging such spool with its driving roller, said devices being intercoupled so that rendering one effective renders the other ineffective, and a pair of shift devices, one for each spool, for rendering the associated coupling device effective, each shift device including a cam rotated by said driving means, and a normally ineffective cam follower rendered effective by the detecting device for the associated spool to enable the cam to set the coupling device for such spool in effective condition when such spool is exhausted.

5. A ribbon feeding mechanism comprising a pair of ribbon feeding units, each unit including a ribbon receptacle, a friction drive roller in said receptacle, a ribbon spool in said receptacle, a roller for supporting said ribbon spool, a control lever having a pair of rollers, one coacting with the supporting roller to hold the spool out of engagement with the driving roller when said lever is in an inactive position and the other roller coacting with the ribbon spool to hold the latter in driving relation with said drive roller when said lever is shifted to an active position, an exhaustion detecting device for said spool, a shift cam, and a cam follower normally out of cooperation with said cam and connected to said lever, said cam follower being shifted into co-

operation with said cam under control of said exhaustion detecting device when the ribbon spool becomes exhausted to enable said cam to actuate said lever to active position; means to actuate the drive rollers and cams of both units, and means interconnecting said levers for positioning the lever of the opposite spool in the inactive position when the lever for the exhausting spool is set in active position by its cam.

6. In a ribbon mechanism, a pair of ribbon spools, a frame work including a pair of pockets, one for each spool, each pocket having a fixed guide roller and a driving roller for rotatably supporting the spool; driving means for said driving rollers; control means including a pair of elements, one for each spool, for lifting the spools out of engagement with their driving rollers to allow the spools to unwind, said means being settable in alternate positions in each of which a different one of said spools feeds while the other unwinds, means to detect exhaustion of said spools, a pair of shift actuators one for each of said spools and actuated by the driving means, and means rendered operative by the detection means when any spool becomes exhausted, to couple the shift actuator for such spool to the control means for such spool whereby to disengage the full spool from its driving roller and engage the exhausted spool with its driving roller.

7. A ribbon feeding mechanism comprising a pair of ribbon spools, a drive shaft having driving members rotatably engaging the rims of said spools, means associated with each spool for engaging such spool with the associated driving member, means interconnecting said engaging means and movable between two alternate positions in one of which positions one spool is engaged with and the other disengaged from the corresponding driving member and in the other of which positions these conditions are reversed, means to detect exhaustion of the ribbon, and means controlled by the detection means for shifting the interconnecting means to cause the exhausted spool to be driven by its driving member and the other spool to be disconnected from its driving member.

8. A ribbon feeding mechanism for office machines comprising a pair of ribbon spools; a pair of detecting devices, one for each spool, for detecting exhaustion of the associated spool; a pair of friction driving rollers, each associated with one of said spools; means to drive said rollers; a pair of devices, one associated with each spool, for bodily moving such spool into and out of engagement with its driving roller, said spool moving devices being intercoupled so that rendering one effective renders the other ineffective; and a pair of shift devices, one for each spool, for rendering the associated spool moving device effective, each shift device including a cam rotated by said driving means, and a normally ineffective cam follower rendered effective by the detecting device for the associated spool to enable the cam to set the spool moving device for such spool in effective condition when such spool is exhausted.

9. A ribbon feeding mechanism comprising a pair of ribbon feeding units, each unit including a ribbon spool, an exhaustion detecting device, a driving member, means to move the ribbon spool into and out of engagement with the driving member, and a shift device rendered effective by the exhaustion detecting device to actuate the spool moving means to move the ribbon spool

into engagement with the driving member when the ribbon spool is exhausted; means to drive said members and said shift devices, and means interconnecting said shift devices and spool moving means to render one spool moving means ineffective when the other is rendered effective.

10. A ribbon feeding mechanism comprising a pair of ribbon feeding units, each unit including a ribbon receptacle, a rotary driving element in said receptacle, a ribbon spool in said receptacle, a control lever having a pair of rollers, one effective to hold the spool out of engagement with the rotary driving element when said lever is in an inactive position and the other roller coacting with the ribbon spool to hold the latter in driving relation with said driving element when said lever is shifted to an active position, an exhaustion detecting device for said spool, a shift actuator, and a coupling element normally out of cooperation with said actuator, and connected to said lever, said coupling element being shifted into cooperation with said actuator

under control of said exhaustion detecting device when the ribbon spool becomes exhausted to enable said actuator to actuate said lever to active position; means to actuate the driving elements and actuators of both units, and means interconnecting said levers for positioning the lever of the opposite spool in inactive position when the lever for the exhausting spool is set in active position by its actuator.
